ATTORNEY.

UNITED STATES PATENT OFFICE.

ANTON HASLINGER, OF PHILADELPHIA, PENNSYLVANIA.

Thermal Circuit-Closer.

1,387,050.

Specification of Letters Patent.

Patented Aug. 9, 1921.

Application filed March 15, 1919. Serial No. 282,870.

To all whom it may concern:

Be it known that I, ANTON HASLINGER, a subject of Austria, residing at Philadelphia, in the county of Philadelphia and State of Pennsylvania, have invented new and useful Improvements in Thermal Circuit-Closers, of which the following is a specification.

The invention relates to alarms and more particularly to thermo-electric alarms for use in connection with heat producing devices, and the object of the invention is to provide an alarm that may be conveniently used in connection with a stove such as the usual gas stove, for the purpose of sounding a bell or other alarm to call attention to the condition of the stove, as to the supply of the gas thereto.

Among other features the invention comprehends an alarm which may be operated by a suitable battery or the like, and which in the event the gas supplied to the stove is blown out or discontinued and then later on re-established, will result in an alarm being given so that the operator can shut off the supply of gas or ignite the same at the burner, as the case may be.

Still further the invention comprehends an improvement over the construction set forth in a United States Patent granted to me December 13, 1904, No. 777,506.

In the further disclosure of the invention, reference is to be had to the accompanying drawings constituting a part of this specification, in which similar character of reference denote corresponding parts in all the views, and in which—

Figure 1—is a fragmentary elevation of a gas stove with parts broken away to disclose the underlying structure.

Fig. 2—is a detailed view of the mechanism I employ, looking at the same in front elevation, with the thermostatic element in inoperative or set position.

Fig. 3—is a similar view showing the thermostatic element in set position to complete a circuit to the alarm.

Fig. 4—is a fragmentary vertical sectional view taken on the line 4—4 in Fig. 3.

Referring more particularly to the views, the numeral 10 indicates a gas stove having a suitable gas supply pipe 11, equipped with the usual gas cock 12, and suitably arranged on the gas stove beneath a bottom 13 thereof, is an electric battery 14 and a bell or other suitable alarm 15, a wire *a*, being connected

from the battery with the bell, with a second wire *b*, from the bell to the structure of the stove, and a third wire *c*, from the battery to a binding post 16, mounted on a substantially circular frame 17 of a part of my device, the binding post 16 however, being suitably insulated from the frame. The frame 17 includes a cross piece 18 and the frame is suitably secured in any manner to the structure of the gas stove, and in a convenient place such as shown in Fig. 1.

Secured to the frame 17 is a thermostatic element 19, which in this instance is shown to consist of a curved sensitive spring like member, capable of being enlarged or reduced as to its diameter, by the action of cold or heat, that is to say, the thermostatic element 19 has suitably hinged thereto, a contact finger 20, which in certain instances, will, due to the action of the thermostatic element 19, when the same cools after being heated, engage with the binding post 16 as shown in Fig. 3.

The frame 17 includes a projection 21 and pivoted on the projection and the frame, is a cam 22, including an operating knob 23 and an off-set tail 24, acting in the capacity of a weight, said tail being supported by a laterally projecting arm 26 mounted on the thermostatic member to maintain the circuit broken. The cam 22 is adapted for operation on the thermostatic element 19, as will be now described in the operation of the device and the frame 17 is further provided with a pivoted stop lug 25, disposed adjacent to the binding post 16, said stop lug 25 being provided for returning the contact finger 20 to the position shown in Fig. 2 when the device is set ready to function as hereafter explained.

Assuming that the device shown in Figs. 2, 3, 4, is attached to the gas stove shown in Fig. 1 in the manner disclosed therein, and the proper electric connections are made as shown, the operation is as follows:

Manipulation of the lever 23 causes the cam 22 to engage the thermostatic member and thus move the contact finger 20 away from the binding post 16, the cam 22 however being retained in contact with the thermostatic element, with the tail 24 disposed off at an angle substantially as shown in Fig. 2. Now when the gas stove is in operation, the heat produced will tend to cause the thermostatic element to actuate to the end that

the thermostatic element will be moved out of engagement with the cam 22 and this action will enable the weight of the tail 24, to actuate the cam by gravity, so as to entirely 5 move it out of its engagement with the thermostatic element and provide sufficient space for the retraction of the thermostatic element at a later period. Now if the gas should suddenly be cut off from the main supply, or be 10 blown out, the cooling off of the thermostatic element will cause the same to move in the opposite direction, bringing the contact finger 20 into contact with the binding post 16 and thus complete a circuit through the 15 structure of the gas stove and the wires *a*, *b*, *c*, to the battery 14 and bell 15, causing the bell 15 to sound an alarm so as to call the attention of the operator, to the fact that the gas supply has been discontinued, or that the 20 flame has been blown out. The operator can now shut off the gas supply by closing the cock 12, or wait until the gas flow is again continued, and igniting the same at the burner of the stove. If the alarm were not 25 provided, the later reestablishment of the flow of gas would cause the room in which the gas stove is located to become filled with gas, which would result in an explosion, if the operator's attention had not previously 30 been called to the fact that the gas flow had been discontinued, by the action of my thermo-electric alarm.

It will be understood that the cam 22, can be reset or placed in proper position by 35 merely manipulating the knob or lever 23, and that the movement of the cam out of the way of the thermostatic element is accomplished by the gravitating movement of the

tail 24, when the thermostatic element initially is disengaged from the cam. 40

From the foregoing description it will be seen that the device described is of a simple construction and consists of few parts that cannot readily get out of order, and that a positive action of the alarm can be readily 45 obtained, especially when the thermostatic element is made highly sensitive to the action of heat or cold, so as to effect a ready action thereof.

Having described my invention, I claim: 50

1. In a thermo-electric alarm the combination with a frame and a thermostatic element mounted on the frame and movable to engage an electric contact, of a weighted cam mounted on the frame and movable to actuate the 55 thermostatic element to normally hold the same out of electric contact, said thermostatic element when subjected to the action of heat, being adapted to release said cam so that the weighted portion thereof will gravitate the cam into a position out of the way of the action of said thermostatic element, enabling the thermostatic element, when the latter cools, to engage said electric contact.

2. In a device of the character described, 65 the combination with a frame and a thermostatic element mounted on the frame and movable to close an electric circuit, a contact member adapted to be engaged by said thermostatic element and a gravitationally movable cam-like member mounted to swing on the frame and movable to engage the thermostatic element and normally hold it out of contact with said contact member. 70

In testimony whereof I affix my signature. 75
ANTON HASLINGER.
